UNITED STATES PATENT OFFICE.

JAMES SCAPAROTT, OF BUTLER, PENNSYLVANIA.

DESIGN FOR A TILE OR SIMILAR ARTICLE.

Application filed March 26, 1925. Serial No. 12,889. Term of patent 7 years.

To all whom it may concern:

Be it known that I, JAMES SCAPAROTT, a subject of the King of Italy, residing at Butler, Pennsylvania, have invented a new, original, and ornamental Design for Tile or Similar Article, of which the following is a specification, reference being had to the accompanying drawings, forming a part thereof, and wherein the figure is a plan view of a single tile bearing my new design.

I claim:

The ornamental design for a tile or similar article, as shown.

JAMES SCAPAROTT.
